UNITED STATES PATENT OFFICE.

NATHANIEL B. WALES, OF NEW YORK, N. Y.

METHOD OF AND STRUCTURE FOR UTILIZING SUPERHEATED LIQUID FUELS.

Application filed May 21, 1920. Serial No. 363,235.

To all whom it may concern:

Be it known that I, NATHANIEL B. WALES, a citizen of the United States, residing at New York, in the county of New York and 5 State of New York, have invented certain new and useful Improvements in Methods of and Structure for Utilizing Superheated Liquid Fuels, of which the following is a specification.

10 This invention relates to a method of injecting and gasifying liquid hydrocarbons and utilizing the same in the cylinders of internal combustion engines.

15 The object of my invention is to convert liquid fuels into a combustible mixture when injected into air under pressure, by subjecting a small quantity of the liquid fuel to a degree of heat and pressure such that when released into an atmosphere of 20 lower pressure, the heat content of the liquid (which exceeds that necessary for evaporation) instantly converts said liquid into a dry gas.

25 In applying this principle to an internal combustion engine I employ a suitable small liquid fuel pump which places the liquid hydrocarbon under a pressure of say 600 lbs. This liquid is then heated while under pressure, at first on starting the motor 30 it may be heated by an electrical resistance element or sufficiently atomized by its own static pressure during release, and during normal operation of the motor by the heat of the exhaust or by heat directly obtained 35 from the cylinder wall or any other source. The liquid fuel, highly heated and under this high pressure, is now ready for use drop by drop into the cylinder of the motor, controlled by a suitable valve measuring mechanism which directly releases it to 40 the clearance volume of the cylinder when the piston is at the top of its compression stroke. The release of the pressure tension on the liquid hydrocarbon produces an instant change of state of the liquid to that of 45 a dry gas which being injected into the air dilates due to its change of state caused by the tremendous expansion of its internal heat content and produces with the air a mixture very explosive or quick burning 50 charge which upon being ignited by an electric spark produces high mean-effective pressures operating at high thermal efficiency due to the completeness of the gaseous state of the combustible mixture therefrom. This process of fuel injection also

produces many beneficial characteristics such as freedom from pre-ignition and the peculiar pre-ignition "knocks" when certain fuel mixtures are subjected to conventional 60 compression temperatures such as kerosene, fuel-oils and etc. which have either a distinct single or dual pre-ignition pressure peak. Then again, the maximum air (oxygen) content can be taken into a given sized 65 motor cylinder because no fuel-vapor is mingled with or displaces the air during the suction and compression strokes, thereby permitting the maximum heat content to be generated per cubic inch of displacement of 70 the cylinder.

I have illustrated an embodiment of my invention in the accompanying drawings in which—Figure 1 is a vertical transverse cross-sectional view of an internal combustion engine equipped with my invention; Fig. 2 is a side elevation of the same, partly in section; Fig. 3 is a vertical sectional view of the pump; Fig. 4 is a sectional view on the line 4—4 of Fig. 3; Fig. 5 is a fragmentary vertical sectional view of the pump cylinder and control valves; Fig. 6 is a top plan view of the same; Fig. 7 is a sectional view on the line 7—7 of Fig. 5; Fig. 8 is a fragmentary enlarged vertical sectional view of the valved preheating plug in the upper part of the engine cylinder; and Fig. 9, is a vertical sectional view on the line 9—9 of Fig. 8.

For the purpose of explaining my invention, I have illustrated a four cylinder four cycle engine. On the initial downward stroke of the piston 2, the valve 5 is opened for the admission of air through the port 6. On the upward stroke the air is compressed 95 in the clearance volume or combustion chamber 8 and just prior to the downward power stroke the fuel is injected, the resulting mixture being fired by the spark at the plug 9. During the succeeding upward stroke the 100 cam shaft 10 lifts the valve 5 to permit the escape of the exhaust gases.

The liquid fuel is supplied to the pre-heater plug and maintained under pressure 105 by a fuel pump.

The frame or casing 15 of the fuel injection pump is bolted at 16 to the frame of the engine. The cross-head 17, to which the pump piston 18 is bolted, is guided in the frame 15 and is actuated by the eccentric 110 19 on the shaft 20, the latter being suitably geared to the crank shaft. The fuel supply

pipe 25, connected with a suitable source, connects with the inlet port 26 which is controlled by the spring-pressed valve 27 carried by the nut plug 28.

5 The fuel is compressed in the pump barrel 30, by the descent of the plunger 18, forcing the valve 31 back against the pressure of its spring, and passing through the channel 34 into the lower portion of the barrel 35, and 10 through the tube 36 to the channel 38 of the heating plug 40. The spring-pressed valve 31 is carried in the bore of the hollow nut 32. The upper portion of the barrel 35 serves as an air cushion to minimize or dampen the 15 pulsations. A gauge 39 indicates the pressure in the system. When the pressure exceeds the predetermined maximum, the valve 41 yields and permits the excess to return to the inlet pipe through the by- 20 pass 43.

The inlet channel 38 of the heating plug 40, connects with an annular laterally extending channel or chamber 45, surrounding a hollow core portion 46, which forms a 25 casing for the electric heating coil 48. The channel 45 communicates with a valve chest 50 through a port or passage 51 at one side of the valve 52, the latter being carried by a pin 53 projecting laterally from the end of 30 a rod or stem 54, which extends through a sleeve 56 in the lower part of the plug and bears upon a short hollow stem 56' carrying at its lower end a roller 57 which rides upon the tapered bearing collar 58 on the rotary 35 shaft 60. When the roller falls into the recess or pocket in the collar 58, the stem 54 is in its lowermost position and as indicated in Figs. 1 and 8, the valve 52 is at that instant in such position that the passage 62 40 registers with a channel or port 64 opening into the chamber or recess containing the heating coil 48. At all other times the roller 57 rides upon the periphery of the collar 58 and raises the valve stem so that it maintains the valve in a position to close the port or passage 64. The shaft 60 which carries the tapered collars or cams 58 may be shifted slightly longitudinally by means of a lever 65 connected to an operating rod 67, for the purpose of varying or adjusting the amount or degree of registration between the passage 62 and the port 64, to thereby vary at will the amount of fuel charge injected into the combustion chamber.

55 During the starting period the fuel is heated within the annular heating chamber by means of the heating coil 48 the terminals 48^a and 48^b of which are connected to a suitable source of electricity, such as a storage battery. After the engine is in operation the heat absorbed by the fuel by its passage through the chamber 45, which chamber is

carefully proportioned to have the necessary heating surface to supply the amount of heat to give a proper change of state of the 65 fuel after its release from the pressure at which it absorbed the heat.

The operation of an engine constructed as above described will be apparent to engineers from the detailed description of the 70 structural parts. The liquid fuel is supplied by the fuel pump and maintained under pressure in the annular heating chamber 45 where it is heated to a temperature approximating its critical temperature at said pressure. The fuel passes continuously from the chamber 45 through the channel 51 into the valve chest 50. At the end of each compression stroke the roller 57 drops into the recess in the cam collar 58 and thereby 80 causes the valve 52 to move until its passage 62 registers more or less with the passage 64. At this instant a charge of preheated fuel under pressure is injected into the compressed air in the clearance volume or combustion chamber 8. The pressure of the liquid fuel being far higher than said body of 85 compressed air, and its heat content equaling its latent heat it instantly expands into a dry gaseous state and combines with the air 90 to form an explosive gas mixture which upon being ignited by the electric spark produces high mean-effective pressures in the cylinder.

As previously pointed out, this process of 95 fuel injection results in a high thermal efficiency due to the completeness of the gaseous state of the combustible mixture. It also gives the highest possible power output from a given sized cylinder due to an explosive 100 type of mixture combined with high working compression. There is an entire absence of pre-ignition and the peculiar pre-ignition "knocks" which occur when certain fuel mixtures are subjected to compression in 105 the usual manner. These beneficial characteristics will be appreciated by engineers.

I claim:-

A fuel gasifying system for internal combustion engines, comprising a member projecting into the clearance volume of the motor having a central bore opening thereto and a heating chamber concentric therewith arranged to preheat liquid fuel therein by the heat generated within the 110 clearance volume, means for supplying liquid fuel under pressure, a valve operating to inject measured quantities of said heated fuel under pressure through said bore into the clearance volume, and means for actuating said valve synchronously with the engine crank shaft.

In testimony whereof I affix my signature.
NATHANIEL B. WALES.
